UNITED STATES PATENT OFFICE

JOSEPH WESOLIK, OF ST. LOUIS, MISSOURI

WRENCH

Application filed October 16, 1931. Serial No. 569,203.

This invention relates to wrenches, and has for its main object to provide a wrench which is of such construction and design that it can be used successfully to turn or rotate a threaded member located in such a position that there is not sufficient space or clearance around the same to permit the use of a conventional wrench of the kind in which the operating shank or handle of the wrench is disposed at right angles to the longitudinal axis of the part which is to be turned or rotated by the wrench.

To this end I have devised a wrench that comprises a shank or operating handle, jaws carried by said shank and arranged so as to project laterally from same at approximately right angles to the shank, and means for adjusting one or both of said jaws so as to vary the size of the space or opening between the jaws. In using such a wrench the operating shank or handle is arranged lengthwise of or parallel to the longitudinal axis of the part or member which it is desired to turn, instead of being arranged at right angles to the longitudinal axis of said part, as in the case of a conventional wrench, and accordingly, my wrench can be used in many places and for many purposes that do not permit the use of a conventional monkey wrench or pipe wrench, due to lack of space or clearance in which to swing the shank of the wrench in the operation of turning or rotating the part on which the wrench is used. In the form of my invention herein illustrated the wrench is equipped with two movable jaws carried by levers or equivalent swinging members pivotally attached to a head piece rigidly combined with the operating shank or handle, and said jaws are adapted to be moved relatively to each other to vary the size of the space between same by manipulating a threaded member on the shank which imparts a sliding movement to a sleeve that embraces the levers on the head piece that carry the jaws.

Figure 1 of the drawing is a front elevational view of my improved wrench.

Figure 2 is a side elevational view of said wrench.

Figure 3 is a front elevational view, showing the jaws fully opened.

Figure 4 is a side elevational view of the wrench, illustrating it being used for turning a coupling on a pipe that is arranged in such a position that it would be impossible to use a conventional wrench to turn or rotate the coupling; and

Figure 5 is a longitudinal sectional view, taken on the line 5-5 of Figure 1, looking in the direction indicated by the arrows.

In the accompanying drawing which illustrates a pipe wrench constructed in accordance with my invention, A designates the operating shank of the wrench, B designates a bifurcated head piece rigidly attached to the upper end of said shank, C designates a handle or cross piece rigidly attached to the lower end of the shank, and D designates a pair of serrated jaws that are disposed at right angles to the shank A. Preferably, both of the jaws D are adjustable or movable, and are carried by a pair of levers E disposed oppositely to each other at opposite sides of the longitudinal axis of the shank A, and pivotally connected at 1 to the head piece B. The levers E are disposed substantially longitudinally of the shank and are arranged in the vertical plane of the head piece B, which, as previously stated, is bifurcated so as to form housings for the levers E. The jaws D are arranged at right angles to the shank A and to the levers E, and accordingly, when the wrench is being used the operating shank A is disposed lengthwise of or parallel to the longitudinal axis of the part that is being turned, instead of being arranged at right angles to said longitudinal axis. Thus, as shown in Figure 4, if the wrench is being used to turn a coupling on a pipe line, the shank A is arranged at one side of the pipe line in parallel relation to same, and the jaws D that engage the coupling project laterally from the upper end of the operating shank. Accordingly, when the user exerts a twisting action on the handle or cross piece C at the lower end of the shank A, the wrench, as an entirety, will travel in a circular path around the pipe line and the jaws will impart a rotary motion to

the coupling α . This is a very desirable characteristic of a wrench, either a monkey wrench or pipe wrench, and makes it possible to use the wrench in many places and for many purposes where the conventional monkey wrench or pipe wrench could not be used, as, for example, in a corner where the part to be turned is located in close proximity to a wall or walls, or in an instance where the part to be turned is located inside of a duct or other passageway of relatively small diameter at a point remote from a hand hole or other opening in the duct that forms the only point of access to the part to be turned.

15 The jaws D are moved towards and away from each other to vary the size of the space or opening between the jaws by manipulating a nut F on the shank A which imparts a sliding movement to a yoke-shaped member G that carries a sleeve H which is adapted to embrace the jaw carrying levers E. When the nut F is turned in a direction to cause it to travel upwardly on the shank A, the sleeve H will slide upwardly over the levers E and exert pressure on said levers in a direction to move the jaws D inwardly towards each other. When the nut F is turned in the opposite direction, it will travel downwardly on the shank A, and thus permit the sleeve H to move in a direction to permit the levers E to swing outwardly so as to separate the jaws D and increase the size of the space between said jaws. The yoke-shaped member G can either be rigidly connected to the sleeve H, or the yoke-shaped member can be constructed in such a way that the side legs of same constitute adjustable operating elements for the levers E. We prefer to construct the wrench in this manner and to this end we use a yoke-shaped member G whose side legs are positioned inside of the sleeve H and are engaged by adjusting screws 2 in said sleeve that are adapted to be tightened so as to force the side legs of the yoke-shaped member G inwardly towards the operating shank A, and thus compensate for wear on the levers E or on the means that is used to move said levers in a direction to reduce the size of the space between the jaws D of the wrench, the side legs of the yoke-shaped member having sufficient resiliency to provide for or permit of such adjustment of the jaw operating means.

Due to the relatively great range of adjustment of the jaws D, it is preferable to mount said jaws on their supporting levers E in such a way that said jaws are capable of being adjusted angularly relatively to the levers E in a direction to cause the gripping faces of the jaws to be disposed parallel to the part which is to be turned by the wrench. To this end I provide each jaw D with a depending leg 3 that is arranged in a bifurcated portion 4 at the upper end of the supporting lever E of the jaw, and pivotally

connected to said bifurcated portion by means of a pivot pin 5. Such a connection between the jaws D and their supporting levers E permits the jaws to be turned into such a position, that when the jaws are in their fully open position, the active faces or serrated faces of the jaws will be disposed parallel to the longitudinal axis of the operating shank A, as shown clearly in Figure 3 of the drawing. Any suitable or preferred means may be used to hold the jaws D in rigid relationship with their supporting levers, after said jaws have been set or adjusted, as above described, the means herein illustrated for this purpose consisting of locking screws 6 carried by the levers E and arranged so that the threads of same frictionally engage mutilated threads or partial threads in the lower ends of the depending legs 3 on the jaws.

As previously stated, my invention is applicable to pipe wrenches and monkey wrenches, and while I prefer to make both jaws of the wrench adjustable, this is not absolutely essential. Various other means than that herein illustrated may be used to adjust the jaw or jaws so as to vary the size of the space between the jaws, and while I prefer to mount the jaws on their supporting levers in such a way that they can be adjusted angularly relatively to said levers, this is a detail of construction that can be dispensed with without departing from the spirit of my invention.

Having thus described my invention, what I claim as new and desire to secure by Letters Patent is:—

1. A wrench, comprising an operating shank adapted to be arranged substantially lengthwise of the longitudinal axis of the part to be turned, a cross piece or handle on said shank at the lower end of same, a bifurcated head piece rigidly attached to the upper end of said shank, oppositely-disposed levers pivotally mounted on said head piece and provided with laterally-projecting jaws, a nut mounted on said shank and adapted to be adjusted longitudinally of same, a yoke-shaped member actuated by said nut and combined with a sleeve that is adapted to embrace said levers and swing them on their axes to vary the size of the space between the jaws, the side arms of said yoke-shaped member being arranged inside of said sleeve and disposed so as to engage said levers, means for adjusting said side arms relatively to said sleeve so as to compensate for wear, and means for enabling the angular relationship between said jaws and levers to be changed.

2. A wrench, comprising an operating shank adapted to be arranged lengthwise of the longitudinal axis of the part to be turned, a head piece on said shank, pivotally mounted levers on said head piece, laterally-projecting gripping jaws pivotally mounted on

said levers and provided with serrated portions, screw-threaded locking devices carried by said levers and arranged in engagement with the serrated portions of said jaws to hold said jaws in adjusted position, and a means adapted to be manipulated by the operator to move said levers relatively to said head piece so as to vary the size of the space between said jaws.

3. A wrench, comprising an operating shank adapted to be arranged lengthwise of the longitudinal axis of the part to be turned, a head piece on said shank, shiftable levers on said head piece provided at their outer ends with bifurcated portions, laterally projecting gripping jaws mounted in the bifurcated portions of said levers and provided with depending legs whose lower ends have mutilated screw threads, screw-threaded locking devices carried by said levers and arranged in engagement with said mutilated screw threads to hold said jaws in adjusted position with relation to the levers, and a means adapted to be manipulated by the operator to move said levers relatively to the head so as to vary the size of the space between said jaws.

JOSEPH WESOLIK.
